UNITED STATES PATENT OFFICE.

FRANK L. CARTER, OF DORSEY, MARYLAND.

HYDROCARBON-BURNER.

SPECIFICATION forming part of Letters Patent No. 667,165, dated January 29, 1901.

Application filed April 17, 1900. Serial No. 13,257. (No model.)

To all whom it may concern.

Be it known that I, FRANK L. CARTER, a citizen of the United States, residing at Dorsey, in the county of Howard and State of Maryland, have invented certain new and useful Improvements in Hydrocarbon-Burners; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention has relation to hydrocarbon-burners, and has for its general object to provide an improved burner of this class adapted for use in ranges, cooking and heating stoves, furnaces, grates, and other analogous structures.

A special object of the invention is to provide improved means whereby the air supplied to the combustion-chamber to facilitate combustion will be heated before coming into contact with the unconsumed vaporized oil or gas or the flames, whereby all danger of chilling is avoided and all possible condensation of unconsumed vapor prevented.

A further object of the invention is to improve the construction of the burner with a view to economy of construction and ready separation or assembling of the parts to facilitate taking down and setting up for repairing or other purposes.

With these objects in view the invention consists in the improved construction, arrangement, and combination of parts of a burner of the class specified, all as fully described hereinafter and afterward specifically claimed.

In the accompanying drawings, in which the invention is illustrated as of a form suitable for use in an oblong fire-box, such as is common in cooking stoves and ranges, Figure 1 is a perspective view of a burner constructed in accordance with this invention. Fig. 2 is a central longitudinal vertical sectional view of the same on the plane indicated by the broken lines $x-x$ of Fig. 3. Fig. 3 is a horizontal sectional view, slightly reduced in scale, on the plane indicated by the broken lines $y-y$ of Fig. 2 looking downward, as in-

dicated by the arrows. Fig. 4 is a top plan view of the base-plate on a still further reduced scale.

Like parts are indicated by the same numerals in all the figures of the drawings.

Referring to the drawings by numerals, 1 indicates the base-plate, which is provided with a vertical peripheral flange 2, making it serve the purpose of a pan, as hereinafter specified. The plate 1 is provided with openings 3 3 and 4 4, surrounded on the upper surface of the plate by flanges 5 of substantially the height of flange 2. These openings are shown circular and as of two series 3 3 and 4 4 on either side of the longitudinal center of the plate. Their shape, however, the number in each series, and the position of each series may be varied to suit the particular circumstances of each case. As before stated, this plate 1 is the base-plate of the burner, and it also forms the base or bottom of a chamber 6, which chamber is completed by the addition of a top plate 7, having a depending peripheral flange 8 fitting inside the peripheral flange 2 of the base-plate. In the top plate 7 are provided two longitudinally-arranged rows of small holes or perforations 9 10, so placed as to be out of register or out of vertical alinement with openings 3 3 and 4 4 of the base-plate, the rows of perforations 9 and 10 being preferably nearer to the sides of the plate 7 than are the openings 3 3 and 4 4 to the sides of plate 1.

11 12 designate two chambers or retorts preferably of oblong rectangular form and of a length somewhat less than the width of chamber 6, such form and size being variable when desired within reasonable limits. These chambers are mounted centrally and transversely at and upon the ends of the top plate 7 of chamber 6 and are secured thereupon in any suitable manner—as, for instance, by means of bolts 13, passing through plate 7, 95 and suitable horizontal lugs or flanges 14, projecting from the bottom of the chambers.

In the inwardly-facing side walls of the chambers 11 and 12 are formed vertical grooves 15 16 to receive vertical flanges 17 18 on the end walls of a combustion-chamber 19, said grooves being closed at their lower ends, so that the flanges 17 and 18 may not pass entirely through them, whereby the chamber 19

will be supported at a suitable distance above plate 7 to provide spaces 20 for the discharge of the products of combustion from the combustion-chamber. The chamber 19 is open 5 at the bottom and also at the top, except that there is provided a central upwardly-curved partial cover 21, provided with a central opening, as hereinafter mentioned.

22 indicates a pipe tapped into retort 11, 10 leading from any suitable supply of oil, (not shown,) which pipe may be provided with any suitable valve for regulating the supply of oil.

23 indicates a horizontal pipe connecting retorts 11 and 12, being tapped into the inner 15 walls of each.

24 indicates a pipe tapped into the inner wall of retort 12 and lying in substantially the same horizontal plane as pipe 23, as at 25, to near the retort 11, where it is curved back, 20 as at 26, and led to the center of chamber 19, where it bends into vertical position, as at 27, its upper end being threaded and projected through the central opening in the partial cover 21 of chamber 19, before mentioned. The 25 pipe 23 and the part 25 of pipe 24 lie just within the lower edge of chamber 19, and the walls of that chamber are notched at 28 to admit said pipes.

The burner proper is indicated at 29 and 30 consists, essentially, of a horizontal pipe closed at its ends and provided with nozzles 30 31, depending vertically therefrom over the openings in the top of chamber 19. The burner 35 proper in this instance is shown as of two short lengths of pipe, as at 32, with caps 33 at their outer ends and connected by a T-fitting 34, the stem of which depends in line with the nozzles and is arranged to be threaded on the projecting threaded end of the vertical portion 27 of pipe 24. When thus attached, the burner bears upon the partial cover 21 of chamber 19, thus securely holding the flanges 17 18 down in the grooves 15 and 16 and securing the chamber 19 in place. Owing 40 to the form of pipe 24, to which the burner 29 is secured when thus acting as a clamping-nut, said pipe will be to a certain extent elastic and yielding, so that any upward expansion of the walls of chamber 19 due to heat 45 will be compensated for and all tendency to strip the threads of part 27 of pipe 24 or of the T-fitting 34 will be avoided.

In operation to start a fire oil is permitted to flow through the pipes, retorts, and nozzles and to drip upon plate 7, where it is ignited. The flame impinging upon the various parts will heat them, so that the oil will 55 soon begin to issue from the nozzles in the form of an inflammable gas or vapor and the 60 jets of flame will be projected downward into the chamber 19 and into contact with all the parts of the burner, heating them to a high degree. The jets will cause a downdraft through the openings in the top of the combustion-chamber, which will supply the oxygen necessary to support combustion, and the products of combustion will pass out of the

combustion-chamber through spaces, taking an upward course between the walls of the chamber and the walls of the fire-box in 70 which the device is used. Without the air heating chamber these products of combustion in passing out through spaces 20 would strike an upward draft of atmospheric air between the walls of the chamber and firebox and the contact therewith would tend to chill the vapors and to condense any unconsumed gas. In such usual construction this mixed air and the chilled vapors would pass up and part of the mixture be again carried 80 through the combustion-chamber, the air in the mixture supplying the necessary oxygen. With the air-heating chamber there would be no side draft of cold air. The air for such side draft will be heated in its passage through 85 the heating-chamber, so that when the vapors of combustion mix with it there will be no chilling and no condensation of unconsumed gases, thus materially facilitating perfect combustion, the result being, as ascertained 90 by practical use, a perfect blue flame and almost entire absence of soot or other residuum. The location of openings 3 3 and 4 4 and perforations 9 10 out of vertical alinement with each other retards the passage of air out of 95 perforations 9 10 before being properly heated. The oil in passing through the retort 11 will be partially or wholly vaporized and the vaporization will be perfected in the passage of oil or vapor through pipe 23, retort 12, pipe 100 24, and the burner, the vapor being retarded, dried, and superheated in its passage through the second retort 12, and this condition being preserved and continued during its further passage through pipe 24 and the burner the 105 vapor will be delivered from the nozzles in condition for perfect combustion.

Should any oil pass into chamber 6 while starting the fire, it will be held therein by flanges 2 and 5 until it is vaporized, passed 110 through perforations 9 10, and consumed, thus preventing it from dripping down into the fire-box or ash-pit and being wasted.

The advantages attending the use of this burner will be obvious from the foregoing description of the construction and operation, and it will be further obvious that slight changes in the construction and arrangement of the parts might be made without departing from the spirit and scope of the invention. 115 120

Having thus fully described the invention, what I claim as new, and desire to secure by Letters Patent of the United States, is—

1. A hydrocarbon-burner comprising an air-chamber forming the base, a combustion-chamber open at the top and bottom and supported a slight distance above said base, burner-jets discharging downward into the top of the combustion-chamber, and openings in the top of the air-chamber outside of 125 and adjacent to the spaces between the sides of the combustion-chamber and the top of the air-chamber, substantially as described. 130

2. A hydrocarbon-burner comprising in its

- construction an air-heating chamber having openings for the discharge of air therefrom, located along the longitudinal edges of the upper wall or cover of the chamber, and a 5 combustion-chamber mounted above the air-heating chamber with spaces along the bottom of its side walls adjacent to and within the vertical planes of the discharge-openings of the air-heating chamber for the discharge 10 of the products of combustion whereby these products are commingled with the heated air, substantially as described.
3. A hydrocarbon-burner comprising an air-heating chamber, and an open-bottom combustion-chamber mounted upon and slightly above said air-heating chamber leaving space 15 for the discharge of the products of combustion under the walls of the combustion-chamber, the air-heating chamber having discharge-openings along the outer edges of its 20 cover outside of the vertical planes of the lower edges of the side walls of the combustion-chamber, substantially as described.
4. A hydrocarbon-burner comprising in its 25 construction an air-heating chamber provided with discharge-openings along the longitudinal edges of its top and admission-openings in its bottom out of vertical alinement with the discharge-openings, and an open- 30 bottom combustion-chamber mounted upon and slightly raised above the air-heating chamber, the side walls of said combustion-chamber being within the vertical planes of the discharge-openings of the air-heating 35 chamber, substantially as described.
5. A hydrocarbon-burner comprising in its construction a base, a retort at each end thereof having oppositely-facing vertical walls provided with vertical grooves in their 40 opposing faces, a combustion-chamber provided with vertical flanges seated in said grooves, an oil-conducting pipe connecting the retorts, and supply-pipe leading from one retort to the burner, substantially as de- 45 scribed.
6. A hydrocarbon-burner comprising in its construction a base, oppositely-facing vertical walls mounted thereon having vertical grooves in their opposing faces, a combustion- 50 chamber provided with vertical flanges seated in said grooves, an oil-conducting pipe secured in one of the walls passing into the combustion-chamber and vertically through the
- cover of said chamber, and a burner threaded upon the projected end of said pipe and 55 serving to secure the combustion-chamber in position, substantially as described.
7. A hydrocarbon-burner comprising in its construction a base, two retorts mounted transversely at the opposite ends thereof, a 60 combustion-chamber mounted above the base and between the retorts, a straight pipe passing through the combustion-chamber and connecting the two retorts, a supply-pipe leading into one of the retorts, a pipe leading from 65 the opposite retort into and projecting above the combustion-chamber, and a burner connected to the projecting end of the last-named pipe, substantially as described.
8. A hydrocarbon-burner comprising in its 70 construction a combustion-chamber, a retort at each end of said chamber, a supply-pipe entering one retort, a pipe connecting the two retorts and passing through the combustion-chamber, a pipe leading from the other retort 75 into and through the combustion-chamber and a burner on the end of the last-named pipe having discharge-nozzles arranged to project their jets into the combustion-chamber and into contact with the pipes, substan- 80 tially as described.
9. A hydrocarbon-burner comprising in its construction a combustion-chamber and an air-heating chamber below the combustion-chamber serving as a support therefor, the 85 air-heating chamber comprising a base-plate with an upward-projecting peripheral flange and openings surrounded by upwardly-projecting flanges and a cover with a depending peripheral flange fitting inside the peripheral 90 flange of the base, a space being formed between the lower edges of the walls of the combustion-chamber and the cover of the air-chamber for the discharge of the products of combustion and the cover of the air-heating 95 chamber being provided with longitudinal rows of discharge-openings adjacent to said spaces and outside the vertical planes of the side walls of the combustion-chamber, sub- 100 stantially as described.

In testimony whereof I affix my signature in presence of two witnesses.
